DESIGN FOR A FUR COLLAR

Albert Rauch, New York, N. Y.

Application June 22, 1939, Serial No. 85,617

Term of patent 3½ years

To all whom it may concern:

Be it known that I, Albert Rauch, a citizen of the United States, residing in New York city, in the county of New York and State of New York, have invented a new, original, and ornamental Design for a Fur Collar, of which the following is a specification, reference being had to the accompanying drawing, forming part thereof.

Fig. 1 is a front view of a fur collar showing my design, and

Fig. 2 is a side view thereof.

The rear view of Fig. 1 is conventional.

I claim:

The ornamental design for a fur collar substantially as shown and described.

ALBERT RAUCH.
